[57] CLAIM

The ornamental design for a front door assembly for a reverse vending machine, as shown and described.

DESCRIPTION

FIG. 1 is a front perspective view from one side of a front door assembly for a reverse vending machine showing my new design; and,

FIG. 2 is a front perspective view from the other side thereof.

The broken line showing of the reverse vending machine in FIGS. 1-2 is for illustrative purposes only and forms no part of the claimed design.
